Attorney.

UNITED STATES PATENT OFFICE

2,298,678

GUNSTOCK

Stanley H. Chase, Otisfield, Maine, assignor of
one-third to Laura L. Chase, Otisfield, and one-
third to Nicolaus Harithas, Mechanic Falls,
Maine

Application March 14, 1941, Serial No. 383,388

5 Claims. (CL. 42—71)

The invention hereinafter to be described relates, in general terms, to improvements in firearms, dealing more particularly with stocks or butts of guns, rifles or other fire-arms, in which a novel feature is incorporated; the novelty consisting in splitting the stock into two substantially similar halves, one of which is a rigid part of the gun, rifle or fire-arm, and the other of which is hinged to swing away from the rigid portion to expose a plurality of depressions on the inner faces of the halves in which depressions various articles may be deposited, the articles being mostly for first-aid use in case of accident or injury to the bearer of the fire-arm or others in his immediate vicinity, and for personal use or convenience.

The articles housed within the stock may comprise a tourniquet, scissors, a roll of bandage, adhesive tape, an antiseptic solution, a restorative, and any other articles which it would be desirable to have available in treating a wound.

The objects of the present invention, are to provide in a stock of a rifle or fire-arm, a first-aid kit carrying and storing therein, first-aid, medical, personal or other useful or necessary articles; to prevent water or dampness from penetrating into the interior of said kit, to eliminate wetting or spoiling of needed or useful articles contained within said kit; to eliminate the necessity for carrying an extra kit for such articles; to prevent the user from forgetting needed articles; and to suggest to the user at a glance what article is actually needed for any particular treatment or other use.

The application, or carrying out of the invention, becomes a possibility whenever or wherever a gun or rifle is being used, as for instance, by sportsmen in the woods, in training camps where real ammunition is being fired for practice purposes, and on the battlefield where it is usually of the utmost advantage that equipment and supplies be readily available for treating and dressing a wound at the earliest possible moment.

As nothing whatsoever pertaining to the operation of the firing mechanism of the gun is involved in my present invention, it is believed that consideration of the stock element alone is all that is necessary to be described and illustrated; and for the purpose of more clearly disclosing my invention I have prepared the accompanying drawing in which like reference characters are employed to identify similar parts in all views.

In the drawing—

Fig. 1 shows a side elevation of the butt or

stock of a gun or rifle, the parts being fully folded and presenting an appearance quite similar to the conventional gun butt;

Fig. 2 is a plan view of Fig. 1;

5 Fig. 3 is a perspective view, showing the parts unfolded, the depressions being shown without the articles which are adapted to be deposited therein;

10 Fig. 4 is a fragmentary, sectional view, showing the hinge connection of the end cover to the rigid half of the stock, the cover being but partially swung away from the ends of the halves of the stock;

15 Fig. 5 is a fragmentary, sectional view, on a somewhat enlarged scale showing, a portion of the structure shown in Fig. 4, and showing the end cover fully closed over the ends of the two halves;

20 Fig. 6 is a perspective view, on a greatly enlarged scale, of the latch member which secures the cover to the two halves;

25 Fig. 7 is a fragmentary sectional view showing the hinge which mutually connects the two halves of the stock, and

30 Fig. 8 is a fragmentary, inverted, plan view illustrating the cover end of the stock, particularly showing the latch and the rubber gasket which is placed between the two halves of the stock to protect the articles deposited in the depressions against dirt and moisture.

35 Referring to the drawing, 1 represents the rigid half of a gun stock and 2 represents the complementary half which is hinged to and swings from the member 1 through the agency of the member 3.

The rigid half 1 has a raised portion 1a on its inner face, the sides 1b of said raised portion closely fitting the walls 2a of the depression 2b in the other half 2 when the parts are brought together as shown in Fig. 2.

40 In the raised portion 1a are numerous depressions 1c of various shapes and sizes adapted to receive any predetermined articles which it is contemplated housing within the gun stock, the articles being omitted from the drawing for the sake of clarity.

45 On the face of the raised portion 1a are pivotally connected metal clips 1d which are adapted to be moved to and from positions in which their free end portions overlie the depressions 1c and thus serve to hold articles in said depressions. The outer end of reference character 1 is represented by part 1e, and the outer end of part 2 is represented by reference character 2e.

50 To secure part 1 and part 2 more firmly when

the two halves are brought together, pins 4 imbedded in part 1, slide in pin holes 4a bored in the inner edge of part 2, as shown in Fig. 7.

Cover 5 is hinged to part 1 at a depression made in the end side of 1e and swings from part 1 through the agency of member 6, while 5a represents the depression in cover 5 adapted to receive the end sides 1e and 2e when parts 1 and 2 and cover 5 are brought together, hinge 6 and depression 5a being illustrated in Fig. 4.

To lock the stock when parts 1 and 2 and cover 5 are brought together, a latch 7 is employed, which latch is shown in a greatly enlarged scale in Fig. 6. The latch 7 is secured to cover 5 by means of a bolt or screw 7a and is provided with a finger clip 7a adapted to be received in a cut-a-way portion 7b formed in adjacent portions of the outer ends of the two halves to permit thumb nail unlatching of the cover when the stock is locked. The latch 7 is provided with pins 7c which pins have their outer ends bevelled to slide in holes 8 bored in the sides of part 1 and part 2 as shown in detail in Fig. 5.

To prevent penetration of moisture or dampness into the interior of the kit when all parts are brought together and the stock is closed, a rubber band or gasket 9 is placed upon the part 1 and overlies the flange which extends from the outer edge of part 1 to the upstanding sides 1b of the raised portion 1a. Reference character 10 represents a conventional ring secured to part 1 and to which one end of the usual shoulder strap may be attached.

While the present improvements as hereinbefore set forth fulfill all the requirements and objects enumerated; it is apparent that modifications in both the structure and the arrangement of parts are possible without departing from the meaning and intent of the invention, I desire, therefore, to be understood as not limiting myself to the exact mechanical and structural details as herein disclosed as, obviously, the invention may be carried out in other ways.

What I claim and desire to secure by Letters Patent is:

1. A two-part stock for guns and rifles, split centrally thereof, one half being adapted to be connected to the fire-arm in the usual manner, the other half having swinging connection with the rigid half on its inner end, a cover enclosing the outer ends of the two halves of the stock, said cover being hingedly connected to the said rigid half, depressions on the inner faces of said halves adapted to receive articles of a predetermined character, and means to positively lock the free end of said cover to and over the outer ends of said split halves.

2. A two part stock for guns, rifles or fire arms, split centrally thereof, one-half being adapted to be connected to the fire-arm in the usual manner, the other half being hingedly connected to the rigid half on its inner end, a cover hingedly connected with the rigid half at the outer end of said rigid half and enclosing the outer ends of the

stock, a plurality of depressions of the inner faces of said halves adapted to receive articles of a predetermined character, means to positively lock the free end of said cover to and over the outer ends of said split halves, and means to open said cover.

3. A two-part stock for fire-arms, split centrally thereof, one-half being adapted to be rigidly connected to the firearm by usual means, the 10 complementary half being hingedly connected to the rigid half on its inner end, pins protruding from the rigid half to slide in holes in the complementary half, a cover hingedly connected to the rigid half and enclosing the outer end of the two 15 halves of the stock, a plurality of compartments on the inner faces of the halves adapted to house articles of a predetermined character, size or length, means to hold articles in said compartments, means to positively lock the free end of said cover to and over the outer ends of said split halves, and means to open said cover.

4. A stock for guns, rifles or fire-arms, made in two parts, one part being adapted to be rigidly connected to the fire-arm in the usual manner, the complementary part having swinging connection with the rigid part on its inner end, pins protruding from the rigid part to slide into holes in the complementary part when both parts are brought together, a cover enclosing the outer ends of the two parts of the stock, said cover having a swinging connection with the rigid part, a plurality of compartments on the inner faces of the two stock-parts adapted to store articles of a predetermined character, size or length, means to hold said articles in said compartments, means to prevent moisture and dampness from penetrating into said compartments when the two stock-parts are brought together, means to positively lock the free end of said cover to and over the outer ends of the stock-parts, and means to open said cover.

5. A two-part stock for guns, rifles or fire-arms, sectionally constructed, one part being adapted to be rigidly attached to the fire-arm in the usual manner, the other part having a swinging connection with the rigid part on its inner end, metal pins protruding from the inner end of the rigid part to slide into holes of the other part when the two parts are brought together, a plurality of depressions on the inner faces of said parts adapted to store articles therein of a predetermined shape, character, size or length, means to hold said articles tightly in said depressions, a cover hingedly connected to the end of the rigid part, said cover enclosing the outer ends of both parts of said stock, means to prevent penetration of moisture or dampness into said depressions when the two parts are brought together and the cover is closed, means to positively lock the free end of said cover to and over the outer ends of said parts, and means to unlatch the cover.

STANLEY H. CHASE.
